CLAIM

The ornamental design for a storage container, as shown and described.

DESCRIPTION

FIG. 1 is a perspective view of the storage container showing my new design, showing the upper lid open and the lower lid partially open to illustrate the storage container has separate compartments on opposite sides;

FIG. 2 is a top plan view of the storage container showing the lids open at right angles to the compartments;

FIG. 3 is a bottom plan view thereof;

FIG. 4 is a right side elevational view thereof, the left side elevational view being a mirror image thereof;

FIG. 5 is a front elevational view thereof; and,

FIG. 6 is a rear elevational view thereof.
